Patented Dec. 15, 1970

219,471

DRINKING GLASS OR THE LIKE

Johannes Klober, Schwelm, Westphalia, Germany, assignor to Firma Hans Klober, Schwelm, Westphalia, Germany, a corporation of Germany

Filed Apr. 16, 1969, Ser. No. 16,765

Claims priority, application Germany Nov. 25, 1968

Term of patent 14 years

Int. Cl. D7—01

U.S. Cl. D36—8

Fig. 1

Fig. 2

FIG. 1 is a perspective view of a drinking glass showing my new design; and

FIG. 2 is a perspective view of a drinking glass showing another form of my new design, wherein the bulged portion is smooth.

The rear view of said embodiments of the drinking glass or the like is identical with the front view, as shown.

I claim:

The ornamental design for a drinking glass or the like, as shown and described.
